(57) **CLAIM**

The ornamental design for a respiratory physiotherapy trainer device, as shown and described.

DESCRIPTION

FIG. 1 is a front perspective view of a respiratory physiotherapy trainer device, showing our new design.

FIG. 2 is another front perspective view of the respiratory physiotherapy trainer device of FIG. 1.

FIG. 3 is a front view of the respiratory physiotherapy trainer device of FIG. 1.

FIG. 4 is a rear view of the respiratory physiotherapy trainer device of FIG. 1.

FIG. 5 is a left side view of the respiratory physiotherapy trainer device of FIG. 1.

FIG. 6 is a right side view of the respiratory physiotherapy trainer device of FIG. 1.

FIG. 7 is a top view of the respiratory physiotherapy trainer device of FIG. 1; and,

FIG. 8 is a bottom view of the respiratory physiotherapy trainer device of FIG. 1.

The broken lines depict portions of the respiratory physiotherapy trainer device that form no part of the claimed design. The dash-dot-dash broken lines in the figures define boundary lines that form no part of the claimed design.

1 Claim, 8 Drawing Sheets
